UNITED STATES PATENT OFFICE.

JOHN B. MURRAY, OF WILMINGTON, ILLINOIS.

RAIL JOINT.

1,413,765.

Specification of Letters Patent. Patented Apr. 25, 1922.

Application filed July 22, 1921. Serial No. 486,768.

To all whom it may concern:

Be it known that I, JOHN B. MURRAY, a citizen of the United States, and a resident of Wilmington, in the county of Will and 5 State of Illinois, have invented a new and useful Improvement in Rail Joints, of which the following is a full, clear, and exact description.

My invention relates to improvements in 10 rail joints, and it consists in the combinations, constructions and arrangements herein described and claimed:

An object of my invention is to provide 15 a device embodying means for connecting adjacent ends of rails and for resisting the stress placed on the rails by the weight of rolling stock passing thereover so that sagging of the rails at the joint is prevented.

A further object of my invention is to 20 provide a device of the character described for connecting rails at their adjacent ends so that the necessity for providing the usual fish plates is obviated.

A further object of my invention is to 25 provide a rail joint in which the device provided for connecting the adjacent ends of rail joints is simple in construction in that it comprises only two identical members and the means for securing the members to one 30 another and to the rails.

A further object of my invention is to 35 provide a device of the character described that is thoroughly effective for the purpose intended, capable of being manufactured cheaply, and practical commercially.

A further object of my invention is to 40 provide a device of the character described that is adapted for use with ordinary rails.

A further object of my invention is to 45 provide a rail joint embodying means for securely holding adjacent end portions of adjacent rails so that lateral movement of each rail at the joint relative to the other rail is prevented.

Other objects and advantages will appear 50 in the following specification, and the novel features of the invention will be particularly pointed out in the appended claims.

My invention is illustrated in the accompanying drawings, forming part of this application, in which—

Fig. 1 is a side elevation of an embodiment of the invention.

Fig. 2 is a plan view of the same,

Fig. 3 is a perspective of one of a pair 55 of connectors embodied in the device.

In carrying out my invention, I provide a pair of unitary connecting members indicated generally at A and B. The connecting members are formed of any suitable 60 material, as for instance steel, that has sufficient inherent strength to withstand the stresses to which they are subjected in service. The members A and B are precisely identical in essential respects and I shall 65 therefore confine my description to the member A, it being understood that like parts are found in the member B and that the same reference numerals have been used for like parts throughout. The member A 70 consists of a body portion 1 having a base 2 extending laterally thereof along its bottom edge and also having a pair of parallel spaced apart lateral extensions 3 and 4 adapted to straddle the web 5 of a rail 75 6 at an end of the latter when the base 2 underlies and supports the bottom flange 7 of the rail. The lateral extensions 3 and 4 replace the usual fish plates and are widened laterally to provide bases 8 and 80 9, respectively, thereby having their under surfaces inclined to conform with the underlying upper surfaces of the bottom flanges of the rail 6 so that the extensions 3 and 4 contact evenly along their entire length 85 5 with the underlying surfaces of the lower flange or base of the rail. The lateral extensions 3 and 4, respectively, are formed with tapering strengthening ribs or webs 90 10 and 11, each having an upper surface 95 flush with the upper surface of the extension with which it is integral. The upper surfaces of the extensions 3 and 4 abut the lower surfaces of the head of the rail 6 when the bases 8 and 9 rest upon the lower flanges of the rail and straddle the web 5 of the rail, as clearly shown in Figures 1 and 2 of the drawings.

The body portion 1 has a relatively reduced portion or vertical extension 13 that 100 will be interposed in substantial alinement with the head portion of the rail 6 so that the upper edge thereof is flush with the upper surface of the rail head and the end walls thereof, which are inclined as shown in Fig. 105 3, are likewise substantially flush with the corresponding sides of the rail head. The extension 13 has its side walls 14 and 15

inclined from their junction with the body portion 1 to the upper end thereof and the wall 16 of the body portion 1 which constitutes the face thereof is inclined from its 5 lower end to the horizontal line indicated at α , which is the line marking the junction of the body portion 1 and the extension 13 and lies in the horizontal plane of the lower surface of the head of the rail 6.

10 From the foregoing description of the various parts of the device, the operation thereof may be readily understood. The rails 6 and 17 joined by my device may be connected between ties 18 as in Fig. 1 or 15 when the ends thereof rest upon a tie as shown in Fig. 2. The members A and B, each comprising the parts which have been described and which are formed integrally with one another, are arranged relative to 20 the ends of the rails 6 and 17 so that the extensions 3 and 4 of the member A straddle the web of the rail 6 which rests at its end on the base plate 2 and the member B is placed in a like position with respect 25 to the rail 17. The rails 6 and 17 are then aligned with the ends thereof positioned as shown in Fig. 1. The faces 16 of the body portions of the connectors will contact along the line α . The body portions 30 are then clamped together by means of relatively large bolts 18 projected through registering openings 19 in the body portions 1, and having nuts 20 screwed thereon. The extensions 3 and 4 which serve as fish 35 plates in my device as well as performing additional functions are connected and secured to the webs of the rails by bolts 21, each of which is projected through registering elongated openings 22 in the extensions 3 and 4 and through the usual bolt hole in the web of the rail that registers therewith.

It will thus be obvious that when the rail ends receive the thrust of a load, such as 45 is occasioned by the weight of rolling stock moving therealong, the body portions 1 will pivot along the line α so that the extensions 13 are moved together and the stress occasioned by the weight of the load is imparted to the extensions 3 and 4 on account 50 of the position of the latter with respect to the heads and bottom flanges of the rails. The stress will therefore be resisted by the members A and B as units and consequently 55 the movement of the rail ends downwardly under stress is reduced to a minimum.

It will be noted that the bolt 21 serves primarily as a means for preventing the rail from slipping out from between the 60 members 3 and 4. The bolt is not drawn down tight, as in the case of ordinary fish plates, hence there is no tendency for the bolt to elongate. Since there is no stress on the bolt, the life of the latter is prolonged.

65 The nuts 20 are tightened to adjust the

positions of the body portion 1 of the members A and B with respect to one another. The line of contact of the adjacent faces of the body portions is along the line indicated at α .

When the body portions 1, contacting at α , are drawn together by tightening the nuts on the bolts, the resulting stress tends to swing the remote ends of the members A and B downwardly. The stress, being resisted, is partly transmitted to the adjacent ends of A and B, tending upwardly immediately under the rail head at their terminals. The stress is thus equally divided, tending upwardly at the adjacent ends of 80 the members A and B and downwardly at the remote ends of the members A and B. It will thus be observed that there is always a tight joint between the rail ends since the body portions 1 will always contact one another along the line α . The device is relatively simple in construction and can be manufactured cheaply.

I claim:

1. A rail joint comprising a pair of connectors each having a body portion adapted to abut the end of a rail and having extensions arranged to straddle the web of the rail and to be secured thereto, and means for securing the body portions of the pair 95 of connectors to one another.

2. The combination with adjacent rail ends of a pair of connectors arranged with their body portions contiguous to and secured to one another to each abut a rail end, 100 each of said body portions being formed with spaced apart integral extensions arranged to straddle the web of the contiguous rail and to bear against the under surface of the rail head and the upper surface of the lower flange of the rail at opposite sides of the web, and means for securing the extensions to the interposed webs.

3. The combination with adjacent rail ends of a pair of connectors arranged with 110 their body portions contiguous to and secured to one another to each abut a rail end, each of said body portions being formed with spaced apart parallel integral extensions arranged to straddle the web of the 115 contiguous rail end to bear against the under surface of the rail head and the upper surface of the lower flange of the rail at opposite sides of the web and with an integral base underlying the bottom flange of the rail for supporting the rail end, and means for securing each pair of the first named extensions to the interposed web.

4. The combination with adjacent rail ends of a pair of connectors arranged with 125 their body portions contiguous to and secured to one another to each abut a rail end, each of said body portions being formed with spaced apart parallel integral extensions arranged to straddle the web of the 130

contiguous rail and to bear against the under surface of the rail head and the upper surface of the lower flange of the rail at opposite sides of the web and with an integral base underlying the bottom flange of the rail for supporting the rail end, means for securing each pair of the first named extensions to the interposed web, said body portions being formed with the contiguous walls thereof inclined to contact with one another along a horizontal line adjacent to the upper edges thereof, said upper edges

being practically alined with the plane of the under surfaces of the rail heads, and each of the body portions being provided with an integral extension having its upper wall practically flush with the upper walls of the rails, with end walls practically alined with the side walls of the rail heads, and with side walls inclined toward the upper end thereof so that the body portions may move relatively under stress about the line of contact with one another.

JOHN B. MURRAY.
